UNITED STATES PATENT OFFICE.

FRED W. FRANKENBERGER, OF LOUISVILLE, KENTUCKY, ASSIGNOR TO STANDARD SANITARY MANUFACTURING COMPANY, OF PITTSBURGH, PENNSYLVANIA, A CORPORATION OF NEW JERSEY.

DESIGN FOR A COMBINATION FAUCET AND SOAP DISH.

Application filed February 8, 1928. Serial No. 25,281. Term of patent 14 years.

To all whom it may concern:

Be it known that I, FRED W. FRANKENBERGER, a citizen of the United States, and residing at Louisville, in the county of Jefferson and State of Kentucky, have invented a new, original, and ornamental Design for a Combination Faucet and Soap Dish, of which the following is a specification, reference being had to the accompanying drawing, forming a part thereof, which shows a perspective view of the article showing my new design.

I claim:

The ornamental design for a combination faucet and soap dish substantially as shown.

FRED W. FRANKENBERGER.
